GEORGE H. PATTISON, OF FREEPORT, ILLINOIS.

WINDMILL.

SPECIFICATION forming part of Letters Patent No. 308,375, dated November 25, 1834.

Application filed February 29, 1884. (No model.)

To all whom it may concern:

Be it known that I, GEORGE H. PATTISON, a resident of Freeport, in the county of Stephenson and State of Illinois, have invented 5 certain new and useful Improvements in Windmills; and I do hereby declare the following to be a full, clear, and exact description of the invention, such as will enable others skilled in the art to which it pertains to make and 10 use the same.

My invention relates to improvements in windmills of the class known as "power" mills, in contradistinction from pumping-mills, and more especially to devices for overcoming 15 or preventing the tendency of the wind-wheel in mills of that class to go out of the wind in consequence of the resistance of the work to be performed. The mechanism employed for this purpose is fully explained and described 20 in the following specification, and shown in the accompanying drawings, in which—

Figure 1 is a central vertical section of a windmill-tower and the mechanism constituting my invention; Fig. 2, a central vertical 25 section of a second tower and a slightly-modified form of the invention; Fig. 3, a central vertical section of a modified form of a part of the gearing shown in Fig. 1; Fig. 4, a plan of the arm *a*, collar *T*, and shaft *M*, shown in Fig. 3; and Fig. 5, a side elevation of the up-right arm *P*, shown in section in Fig. 3.

In all the figures the arrows on the gears indicate motion in the same direction as if they were shown in elevation instead of in section. 35 Thus the lower half of beveled gear *F* of the wind-wheel shaft is meant to be represented as moving from front to rear, or away from the eye.

In Fig. 1, *A* is a windmill-tower of ordinary 40 form; *D*, the top plate attached rigidly thereto, and *C* the turn-table, in which the wind-wheel shaft *c* is journaled. The turn-table rests on a series of anti-friction balls rolling in an 45 annular groove in the upper surface of the plate *D*, the upper part of each ball resting in a corresponding groove in the lower face of the turn-table. A vertical hollow shaft, *M*, whose axis is coincident with the vertical axis of the mill, is journaled at the upper end in 50 the top plate of the turn-table, and at the lower end in the upper end of a second vertical hollow shaft, *M'*, provided with an integrally-

formed shoulder, *m*, which rests on a bearing, *V*, the bearing *V* being supported by a central cross-timber, *B*. 55

On the inner end of the wind-wheel shaft *c* is rigidly mounted a miter-gear, *F*, which engages with a similar gear, *E*, mounted rigidly on the vertical shaft *M*, and also with a third gear, *G*, rigidly mounted on a sleeve, *O*, which 60 turns freely on the shaft *M*.

At the lower end of the sleeve *O* is a miter-gear, *H*, rigidly mounted on the sleeve, and necessarily turning in the same direction as the gear *G*, mounted on the upper end of the 65 sleeve; and on the lower end of the shaft *M* is a rigidly-mounted gear, *L*, which turns in the same direction as the gear *E*, which is mounted on the upper end of said shaft. The gear *L* rests on the upper end of the shaft *M'*, 70 and thus supports the shaft *M*, to which it is fastened.

Immediately below the horizontal gear *H*, and engaging with it, is a vertical beveled gear, *I*, mounted on a horizontal shaft, *e*, which 75 is journaled in a stationary bearing, *f*, and immediately below the vertical gear *I*, and engaging with it, is a double-faced beveled gear, *J J'*, mounted loosely on the shaft *M* and turning freely about it. 80

Below the gear *J J'* is a collar, *o*, surrounding the shaft *M*. A similar collar, *p*, rests on the beveled gear *L*, and between the two collars *o p* is a sleeve, *a'*, formed integrally with a horizontal shaft, *a*, on which is loosely 85 mounted a vertical beveled gear, *K*, which engages with the beveled gear *L*, and the lower face, *J'*, of the double gear *J J'*. The collars *o p* and sleeve *a'* form a continuous sleeve, resting on the gear *L*, and supporting the double 90 gear *J J'*, which is thus held in engagement with the vertical gear *I*. The outer end of the horizontal shaft *a* enters a vertical arm, *P*, which is formed integrally with a crank, *P'*, attached to or formed integrally with the lower 95 vertical shaft, *M'*. As shown in Fig. 1, the end of the shaft enters a hole of suitable size bored in the arm *P*. It may, however, enter a slot, *S*, in the arm, as shown in Fig. 3, and since the weight of the shaft *a* and gear *K* is 100 supported directly by the gear *L* and shaft *M'* it is unnecessary to make the arm *P* support any part of it. The use of the slot renders any vertical binding of the parts impossible,

and for that reason I think it preferable to the form shown in Fig. 1.

The movement of the mechanism shown in Fig. 1 so long as the wind-wheel turns on its axis without moving about the vertical axis of the mill is as follows: The gear F of the wind-wheel shaft turns in the direction indicated by the arrow on the gear—that is, the lower half of the gear moves from front to rear; therefore the left-hand half of the gear E and the right-hand half of the gear G move from front to rear, as indicated by the respective arrows. The gear H on the lower end of the sleeve O moves in the same direction as the gear G, and the gear L on the lower end of the shaft M turns in the same direction as the gear E. The loose double gear J J', being connected with the gear H by a single vertical beveled gear, I, moves in a reverse direction from the gear H, and consequently turns in the same direction and at the same speed as the gear L. The consequence is that the gear K, which engages with the gears J' L, has no rotation whatever on its horizontal axis, but is rotated about the vertical axis of the mill in the direction of rotation of the gears J' L, carrying with it its shaft a, the vertical arm P, the crank P', and the vertical shaft M', to which the crank is attached, and since this motion of the shaft M' is produced by the equal rotation in opposite directions of the gears E G it follows that if power be applied directly to the shaft M' to rotate it the gears E G will thereby be rotated at the same speed in opposite directions, and that their rotation will turn the wind-wheel about its horizontal axis without tending in any degree to turn it about the vertical axis of the mill, or, in other words, without tending to carry it "out of the wind." On the other hand, if the wind-wheel be rotated in either direction about the vertical axis of the mill, without turning on its shaft, it rotates the gears E G in the same direction, and consequently the gears J' L are turned in opposite directions. The result of this opposite rotation of the gears J' L is that the gear K turns on its horizontal shaft without tending to move around the vertical axis of the mill. The foregoing explanation of the operation of the mechanism shown in Fig. 1 may then be summarized as follows: first, the rotation of the wind-wheel on its axis rotates the vertical shafts M' M in the same direction; second, the rotation of the wind-wheel about the vertical axis of the mill rotates the shaft M, but not the shaft M'; third, the resistance offered by the work to the rotation of the shaft M' tends to retard the motion of the wind-wheel about its horizontal shaft, but has no tendency to move it about the vertical axis of the mill; fourth, the simultaneous rotation of the wind-wheel about its horizontal shaft and about the vertical axis of the mill rotates the gear K about its horizontal shaft, and at the same time about the vertical axis of the mill, the comparative speed of the two mo-

tions of the gear being determined by the relative speed of the two motions of the wind-wheel.

In the mill shown in Fig. 2 the arrangement of the tower, turn-table, wind-wheel shaft, and vertical shafts M M' is substantially the same as in the form shown in Fig. 1. The gear F of the wind-wheel shaft, the gears E L, 75 mounted on the shaft M, the sleeve O, and the gears G H, mounted thereon, and the gear I, which transmits motion from the gear H to the gear J, are all in the same relative positions as the similarly-lettered parts in Fig. 1. 80 The face J' of the double-beveled gear J J' is on the same side of the gear as the face J instead of on the opposite side, as in the form shown in Fig. 1. The gears L J' rotate in the same direction when the wind-wheel turns on its shaft, and thus carry the gear K about the vertical axis of the mill and rotate the shaft M'. The shaft a on which the gear K is mounted is formed integrally with the shaft M', or rigidly fastened to it without the 85 interposition of the vertical arm P and crank P' 90 shown in Fig. 1. The operation of the mechanism is precisely the same as that of the device shown in Fig. 1, but in the form shown in Fig. 2 the gears J' K L are within the 95 rectangle formed by the gears H I J, instead of below the corresponding gears, as shown in Fig. 1.

In the mill shown in Fig. 2 the shaft M' is supported by means of a collar, s, rigidly attached to it and resting on the bearing V, in which the shaft M' is journaled, and the shaft M is supported by means of the gear L, which is rigidly fastened to it and rests on the upper end of the shaft M'. In both the mills 100 shown the bearing V of the shaft M' and the bearing f of the horizontal shaft e are formed of a single casting. This is not essential, of course, but adds materially to the rigidity of the frame and to the smoothness of the operation of the gearing. In both the mills, also, the hollow shafts M M' lie in the same vertical line and form a continuous tube. This is a very important advantage, since the cord for drawing the mill out of the wind can pass 105 downward from the mill to the ground through the tube, and works much freer than when it passes through a tortuous and obstructed course. I consider it preferable, also, to take the power from the vertical shaft M' at the 110 base of the mill rather than to transmit it first from the vertical to a horizontal shaft and thence to the ground by means of a belt, as is done in many mills of this general class.

Having now described my invention and explained its operation, what I claim as new, and desire to secure by Letters Patent, is—

1. In a windmill of the class described, the combination of the wind-wheel shaft, two independently-journaled and independently-rotating vertical shafts, and gearing, constructed substantially as described, and connecting said wind-wheel shaft with said vertical shafts, respectively, whereby the rotation of the wind-

wheel shaft in its bearing rotates said vertical shafts in the same direction.

2. In a windmill of the class described, the combination of the wind-wheel shaft, two independently-rotating vertical shafts lying in the same straight line, and gearing, constructed substantially as described, and connecting said wind-wheel shaft and said vertical shafts, respectively, whereby the rotation of said wind-wheel shaft in its bearing rotates said vertical shafts in the same direction and at the same rate of speed.

3. In a windmill of the class described, the combination of the wind-wheel shaft, two independently-journalized vertical shafts standing in the same straight line, and gearing connecting said wind-wheel shaft with said vertical shafts, respectively, whereby the rotation of the bearing of the wind-wheel shaft about the vertical axis of the mill rotates the upper of said vertical shafts, but not the lower.

4. In a windmill of the class described, the combination of the wind-wheel shaft, two independently-journalized vertical shafts lying in the same straight line, and gearing connecting said wind-wheel shaft with said vertical shafts, respectively, whereby the simultaneous rotation of the wind-wheel shaft in its bearing and of the bearing about the vertical axis of the mill rotates said vertical shafts in the same direction, but at different rates of speed.

5. In a windmill of the class described, the combination of the wind-wheel shaft, two independently-journalized vertical shafts, and gearing connecting said wind-wheel shaft with said vertical shafts, respectively, whereby the rotation of said wind-wheel shaft in its bearing rotates said vertical shafts in the same direction, and whereby the rotation of the bearing of the wind-wheel shaft about the vertical axis of the mill rotates the upper but not the lower of said vertical shafts.

6. In a windmill of the class described, the combination of the wind-wheel shaft, two independently-journalized vertical shafts lying in the same straight line and coincident with the axis of the mill, the lower of said vertical shafts being the power-transmitting shaft of the mill, and gearing connecting said wind-wheel shaft and said lower vertical shaft, whereby the reaction of the work upon said lower vertical shaft tends to retard the motion of the wind-wheel on its horizontal shaft, but not to rotate it about the vertical axis of the mill.

55 7. The combination of the wind-wheel shaft *c*, vertical shafts *M M'*, beveled gear *L*, rigidly mounted on the shaft *M*, and beveled gear *J'*, loosely mounted thereon, beveled gear *K*, engaging with said gears *J' L* and connected with the shaft *M'* by means adapted to insure their uniform rotation about the vertical axis of the mill, and gearing connecting the wind-wheel shaft *c* with said gears *J' L*, respectively, whereby the rotation of the wind-wheel shaft in its bearing rotates said gears *J' L* in the same direction and carries the gear *K* about the vertical axis of the mill, and whereby the

rotation of the bearing of the wind-wheel shaft about the vertical axis of the mill rotates said gears *J' L* in opposite directions, and thus rotates said gear *K* on its axis.

8. The combination of the wind-wheel shaft *c*, vertical power-transmitting shaft *M'*, a loosely-mounted gear-wheel free to rotate about the vertical axis of the mill, and connected with the shaft *M'* by means adapted to insure their uniform rotation, and gearing connecting said wind-wheel shaft with said loosely-mounted gear, whereby the rotation of said wind-wheel shaft in its bearing rotates said gear-wheel about the vertical axis of the mill, and whereby the rotation of the bearing of the wind-wheel shaft about the vertical axis of the mill rotates said gear-wheel on its axis.

9. The combination of the wind-wheel shaft *c*, vertical shaft *M*, loosely-mounted gear-wheel *K*, free to rotate about the shaft *M*, and gearing connecting said wind-wheel shaft and said gear-wheel *K*, whereby the rotation of the wind-wheel shaft in its bearing rotates said gear-wheel about the shaft *M*, and whereby the rotation of the bearing of the wind-wheel shaft about the vertical axis of the mill rotates said gear-wheel on its own shaft, substantially as shown and described, and for the purpose set forth.

10. The combination of the wind-wheel shaft *c*, vertical shaft *M*, and sleeve *O*, rotating thereon, beveled gear *F*, mounted on said wind-wheel shaft, beveled gears *E G*, mounted on the upper ends of the shaft *M* and sleeve *O*, respectively, and engaging with said beveled gear *F*, gear-wheel *L*, mounted on the lower end of the shaft *M*, and engaging with a loosely-mounted gear-wheel free to rotate about the vertical axis of the mill, gear-wheel *H*, mounted on the lower end of the sleeve *O*, and engaging with a gear-wheel loosely mounted on a stationary shaft, and a gear-wheel loosely mounted on the shaft *M*, and connecting the loosely-mounted gear-wheels which engage with the gears *H L*, respectively, substantially as and for the purpose set forth.

11. The combination of the wind-wheel shaft *c*, vertical hollow shafts *M M'*, forming a straight continuous tube, and gearing, substantially as described, connecting the wind-wheel shaft with said vertical shafts, respectively, whereby the rotation of said wind-wheel shaft in its bearings rotates said shafts *M M'* in the same direction.

12. The combination of the gear-wheel *I*, mounted on a shaft journalized in a stationary bearing, gearing engaging said gear-wheel at one point and connecting it with the wind-wheel shaft, and gearing engaging with said gear-wheel at an opposite point and connecting it with the vertical power-transmitting shaft of the mill, substantially as shown and described, and for the purpose set forth.

13. The combination of the shaft *M*, shaft *a*, sleeve *a'*, formed integrally with the shaft *a*, and turning freely on the shaft *M*, and gear-wheel *K*, mounted on the shaft *a*, substantially

as shown and described, and for the purpose set forth.

14. The combination of the shaft *c*, vertical shaft *M*, and gears *E F G H I J J' K L*, all 5 constructed, combined, and operating substantially as shown and described, and for the purpose set forth.

15. The combination of the horizontal shaft *c*, the vertical power-transmitting shaft *M'*, 10 and the single casting *V*, in which said shafts

are journaled, substantially as shown and described, and for the purpose set forth.

In testimony whereof I have signed this specification in presence of two subscribing witnesses.

GEORGE H. PATTISON.
